ELECTRIC SYSTEM

Harold E. Edgerton, Belmont, Mass.

Original application August 16, 1933, Serial No. 685,501. Divided and this application February 16, 1944, Serial No. 522,662

12 Claims. (Cl. 315—261)

1

The present invention, though having fields of more general usefulness in electric systems, is particularly related to electrical-energy flash-producing devices and stroboscopes, and to the production of intermittent or flashing light. The present application is a division of application Serial No. 685,501, filed August 16, 1933.

In the said application, there is disclosed a new and improved system for producing strong and intense substantially uniform pulses of electric energy, which may, for example, be utilized for the production of light flashes, by charging or discharging a condenser quickly, reliably and accurately at high frequency through a gaseous-conductor device. That feature of the invention that relates to the production of the pulses during the charging of the condenser is claimed in the present application.

The invention will now be described in connection with the accompanying drawings, the single figure of which is a diagrammatic view of circuits and apparatus arranged and constructed according to one embodiment of the invention.

As described in the said application, a luminescent vapor electric gaseous-discharge flash lamp or flash tube 2 or 7 is provided with two internal main or principal electrodes 4 and 6 in a glass-tube envelope.

For reasons that will hereinafter appear, the first tube 7 may be referred to as a stroboscopic charging rectifier tube and the second tube 2 as a stroboscopic discharging rectifier tube. As these tubes 2 and 7 are identical, however, it will suffice to describe only one of them. They may be of the normally non-conductive rectifier type described in Letters Patent 2,181,879, of December 5, 1939, reissued as Letters Patent 22,123, June 23, 1942, and Letters Patent 22,260, February 2, 1943. Reference may be made to the said Letters Patent for details. Other means than the illustrated tube 2 or 7 may also be used in accordance with the present invention. The principal electrodes 4 and 6 of the gaseous-conductor tube 2 define a normally ineffective principal-current path for the tube 2 and the principal electrodes 4 and 6 of the gaseous-conductor tube 7 define a normally ineffective principal-current path for the tube 7.

The gaseous-conductor means 2 or 7 is described in the said application as of the low-impedance mercury-arc gaseous-conductor type, the internal electrode 4 being shown as in the form of a liquid pool of mercury, used as a cathode, and the internal electrode 6 serving as a anode or plate. The remarks throughout this

specification concerning mercury-arc tubes or lamps apply equally well to the tubes or lamps filled with other gases, with or without mercury vapor.

The pressure of the mercury or other gas or vapor in tubes of this nature is normally of such value as to render the gaseous-conductor means 2 or 7 normally non-conductive, deenergized or ineffective. The gas may become ionized, however, in response to the energization of a normally unenergized control-grid triggering or starting electrode 100, to facilitate the rendering conductive or the starting of the tube 2 or 7, by initiating current flow in the principal-current path including the gaseous medium of the tube 2 or 7 defined by the principal electrodes 4 and 6. This initiation and starting are effected through the medium of a control or starting current path extending from the starting electrode 100.

The electrode 100 is shown in the said application as an external metal-band condenser electrode, situated around the glass of the envelope of the lamp 2 or 7, outside the mercury pool 4, opposite to the meniscus of the mercury. Other types of control-grid or starting electrodes, including electrodes of the internal type, may also be employed.

Direct-current voltage is shown as derived from any desired conventional source of alternating energy of suitable voltage and frequency, through a transformer. The primary winding 144 of the transformer is shown connected to the alternating-current source, and the secondary winding 147 to the anodes of two thermionic or gaseous-discharge half-wave rectifier-tube units 20 and 22 of a common conventional type of full-wave rectifier-and-filter arrangement. The positive terminal of the rectifier source of energy is represented by the cathodes of the rectifiers 20 and 22, and the negative terminal is disposed at an intermediate tap of the secondary winding 147 of the transformer. Impedances 23 and 23a and a reservoir condenser 25 are shown connected in series between these positive and negative terminals across a filter condenser 24, which may constitute part of the conventional source of direct current. A continuous supply of direct-current energy is thus continuously maintained between the positive and negative terminals of the reservoir condenser 25. A lead conductor 10 is connected to the positive terminal of the reservoir condenser 25 and a lead conductor 11 is connected to the negative terminal at times

when normally non-conductive tube 7 is rendered conductive.

A main discharge capacitor or condenser 26 is connected to the terminals of this reservoir-condenser source 25 of direct-current potential, in series with the gaseous-conductor means 7 in the principal-current path of the gaseous-conductor means, in order normally to charge the capacitor or condenser 26 with energy at a predetermined rate from this source 25 when this principal-current path is rendered effective. According to the embodiment of the invention herein illustrated and described, the capacitor or condenser 26 is connected to the source of direct-current potential 25 in parallel with the gaseous-conductor device 2, so that the capacitor 26 is connected between the principal electrodes 4 and 6 of the discharge device 2. These principal electrodes 4 and 6 are therefore connected to the terminals of the condenser source 25 of energy at the same time that energy is supplied to the condenser 26 from the source 25 of direct current. The positive terminal of the condenser 26 is connected to the positive terminal of the reservoir condenser 25 by the lead conductor 10, and to the anode electrode 6 by a lead conductor 9; and the negative terminal of the condenser 26 is connected to the cathode electrode 4 by a lead conductor 8, and to the negative terminal of the reservoir condenser 25 at times when the normally non-conductive tube 7 is rendered conductive.

A resistor 148 is connected in parallel with the reservoir condenser 25 to discharge the circuit when the power is turned off. The condenser 25 should be large in capacity when compared to the flash condenser 26. Also, the condenser 25 should be of a type that has low internal impedance so that the current surges can be produced to produce short flashes of light as may be required for stroboscopic purposes.

The charging circuit for the condenser 26 may be traced from one terminal of the reservoir condenser 25 by way of the conductor 10, and through the condenser 26 and the resistor 149, in parallel, to the anode 6 of the tube 7; then through the mercury vapor of the tube 7 to its cathode 4; and then, by way of the conductor 11, to the other terminal of the reservoir condenser 25. When the tube 7 is deenergized, the condenser 26 is effectively disconnected from the reservoir condenser 25.

Energy is thus fed to the condenser 26 from the source of direct current, to charge the condenser 26, in the form of current pulses that flow through the charging tube 7. This energy is fed through the impedance of the wires 10 and 11, creating a difference of potential between the cathode 4 and the anode 6 of the tube 2. Before each flash, the condenser 26 is charged from the direct-current source so that the anode is positive. The usual voltage to which the condenser is charged is from 200 to 2000 volts.

The quantity of stroboscopic light is determined by the amount of energy in the condenser 26 and by circuit conditions. The capacity of the condenser 26 is increased until there is sufficient average light for the particular frequency of flashing and the extraneous illumination. Slow speeds require a larger amount of light per flash than fast speeds to give the same average illumination. It is necessary to have very bright flashes when the speed of flashing is slow.

After becoming thus charged, the condenser 26, as will presently be more fully explained, may

be discharged through the gaseous medium of the tube 2, between the anode 6 and the cathode 4. The discharging circuit for the condenser 26 is shown extending from the positive terminal 5 of the condenser 26, by way of the lead conductor 9, to the anode electrode 6 of the tube 2; then, through the gaseous medium of the gaseous-conductor tube 2, to the cathode electrode 4; and from the cathode electrode 4, by way of the lead conductor 8, to the negative terminal of the condenser 26. The cathode 4 and the anode 6 of the gaseous-conductor device 2 are thus connected by the lead conductors 8 and 9 to the condenser 26. Because of the direct metallic-wire connection, the condenser 26 is enabled to discharge with relative rapidity through the gaseous-conductor tube 2 between the anode electrode 6 and the cathode electrode 4 when the gaseous-conductor tube 2 becomes conductive.

The discharge current thus obtained from the condenser source 26 of energy results in the production of an electric-energy pulse through the tube 2. This results in the production of a light flash of high illumination intensity and short duration through the tube 2.

The discharge of the condenser 26 through the condenser-discharge circuit above described is initiated by energizing the normally unenergized starting electrode 100, to apply a potential between this electrode 100 and the principal cathode 30 electrode, under the control of a trip circuit. The trip circuit is shown comprising a normally non-conductive or ineffective gaseous-discharge trigger tube device 140, a small auxiliary capacitor 35 or condenser 28, a second suitable direct-current source of energy, such as a second battery 101, or some rectified source of alternating energy, for charging the small auxiliary condenser 28 at a predetermined rate, and a normally ineffective triggering or trip flash transformer 30.

For definiteness, the larger flash condenser 26 may be referred to as a first condenser, and the small auxiliary condenser 28 as a second condenser.

The gaseous-conductor device 7 is provided with a similar trip circuit the elements of which are designated by the same reference numerals, with the additional letter *a*.

The gaseous-discharge device 140 or 140a may be constituted of a mercury-vapor thyratron, a gas-filled hot-cathode thermionic tube, a grid-controlled cold-cathode arc-discharge tube or any other suitable discharge device. The transformers 30 and 30a may be of the high-ratio 55 step-up or any other desired type, with a relatively low-impedance primary winding 36 or 36a, and a secondary winding 29 or 29a, shown connected between the cathode 4 and the external electrode 100. The before-mentioned starting-current or control path of the tube 2, extending from the starting electrode 100 to the cathode 4, includes the inductance of the secondary winding 29.

The trip circuit comprising the thyratron 140 65 may perform its function of initiating the discharge of the condenser 26, through the above-described discharging circuit, by converting the direct current of the source 25 of potential into very sudden voltage pulses in the primary winding 36 of the flash transformer 30. These, as will be described more fully presently, will be manifested as alternating-current pulses in the secondary winding 29.

Each of the trip circuits is provided with a 75 normally unenergized control input circuit and

an output circuit. The output circuits of these trip circuits, or of the thyratrons 140 and 140a, may be traced from the cathode 48 or 48a, through the small second condenser 28 or 28a, serving as sources of energy for the respective output circuits, and the primary winding 36 or 36a of the flash transformer 30 or 30a, in series, to the anode 52 or 52a.

The control input circuits of the trip circuits may be respectively traced from the cathode 48 or 48a, through the impedance 31 or 31a, shown as resistors, and the secondary winding of a transformer 51 or 51a, to the control-grid electrode 50 or 50a.

As soon as the normally non-conductive gaseous-discharge trigger tube 140 or 140a of the trip circuit is rendered conductive, the energy of the small condenser 28 or 28a is discharged through both the thyratron 140 and the primary winding 36, or the thyratron 140 and the primary winding 36a, in series.

The discharging circuit for the small condenser 28 or 28a in the trip circuit may be traced from one terminal of the condenser 28 or 28a, through the tube 140 or 140a and the primary winding 36 or 36a, in series, to the other terminal of the small condenser 28 or 28a.

If the impedance 31 is reactive, or if there are other circuit conditions such that the grid voltage exceeds the critical starting potential, the thyratron circuit may, under certain conditions, generate its own oscillations at a frequency determined by the circuit constants and the characteristics of the tube. The impedance 31 may be made adjustable, in order to vary the charging rate of the condenser 28 and this, in turn, regulates the frequency of the high-voltage surges that are applied to the external electrode 100.

The trigger thyratron tube 140 is connected across an impedance 33, shown as a bleeder resistor, connected in parallel with the condenser 28. This resistor 33 receives energy from the battery 101, in series with the resistor 31, wherein power is obtained for the thyratron 140 and the condenser 28.

The bleeder resistance 33 allows a small current to flow, in order to maintain the proper voltage bias upon the grid 50. The grid 50 is connected so that it is negative with respect to the cathode 48. The resistance 33 is sometimes adjusted to prevent the self-operation of the thyratron 140 when the condenser 28 becomes fully charged. The grid 50 may be connected to various taps on the resistance 33 or 31, respectively, to cause the thyratron 140 to oscillate as a relaxation oscillator of the self-driven type. Power is thus obtained for the thyratron 140 or 140a and for charging the small second condenser 28 or 28a in the output circuits of the trip circuits from the battery 101, in series with the resistor 31 or 31a. The trip-circuit output circuit, comprising the primary winding 36 or 36a, the tube 140 or 140a and the small second condenser 28 or 28a, in series, may therefore be regarded as obtaining its energy from this small condenser 28 or 28a, after becoming charged from the battery 101.

The conversion effected by the trip circuits of the direct current of the battery 101 into alternating-current pulses may be effected by the before-described discharge of the small condenser 28 or 28a through the primary winding 36 or 36a of the flash transformer 30 or 30a.

The control-grid electrode 50 or 50a may be

caused to determine the exact instant when the normally non-conductive thyratron 140 or 140a shall become conductive. This control by the grid electrode 50 or 50a may be exercised by suitably modifying the potential difference between the negatively biased control grid 50 or 50a and one of the principal or main electrodes, as the cathode 48 or 48a, to a predetermined critical value in order to energize the normally unenergized control input circuit of the trip circuit. This may be effected by subjecting the control grid 50 or 50a to a suitable stimulus, as will be described hereinafter. The normally open output circuit of each of the trip circuits thereupon becomes closed or completed from the anode 52 or 52a to the cathode 48 or 48a, in series with the low-impedance primary winding 36 or 36a and the small second condenser 28 or 28a.

The potential may be impressed upon the control electrode 50 or 50a intermittently or periodically, in order to transmit intermittent or periodic pulses in the corresponding control or starting-current path for periodically or intermittently impressing potentials upon the corresponding control or starting electrode 100. The tubes 2 and 7 are thus suddenly rendered conductive intermittently or periodically to produce intermittent or periodic flashes.

The thyratron or other gaseous-discharge tube 140 serves as a relay for accurately timing the starting of the mercury-arc tube 2.

The thyratron does not conduct current when there are no impulses in the grid circuits, except when used for self-oscillation, as described. A timing impulse coming into the input or grid circuit, to stimulate the grid 50, trips the thyratron 140, establishing a high-potential gradient between the electrode 100 and the cathode 4, thereby starting the lamp 2. The time of starting is controlled by the potential on the grid 50. The impulse is effected through the trip or grid transformer 51 when the potential of the grid 50 is raised to a certain critical value with respect to the cathode 48, in response to the stimulus applied to it, so that the light flashes are controlled in accordance with the pulses of the transformer 51. At each cycle, the grid 50 becomes sufficiently positive with respect to the cathode 48 of the thyratron 140 to render the thyratron conductive.

At the instant that the grid potential reaches the critical value, positive with respect to the cathode 48, in response to the stimulus applied to the grid 50, the output circuit of the thyratron tube 140 is completed from the anode 52 to the cathode 48, through the primary winding 36 and the condenser 28. The energy stored in the condenser 28 is then suddenly discharged through the output circuit of the thyratron tube 140, between the anode 52 and the cathode 48, and through the low-impedance primary winding 36 of the step-up transformer 30, virtually short-circuiting the resistor 33 and placing full voltage on the resistor 31. This very quickly and suddenly induces magnetically a high voltage for a brief interval of time in the secondary winding 29. A high voltage is thus suddenly applied to the external electrode 100. The cathode 48 is thereupon raised to nearly the potential of the anode 52 during the discharge, and the grid 50 is given a sudden and very strong negative bias.

This suddenly applied relatively high voltage produced by the potential on the grid 50 across the terminals of the secondary winding 29 will cause a bright cathode spot to form on the sur-

face of the mercury cathode 4 and at the junction between the mercury and the inner wall of the glass tube. The gas in the tube becomes thereupon ionized. The bright mercury spot constitutes a source of electrons upon the mercury, in the vicinity of the cathode 4, that supplies electrons for ionizing the normally un-ionized gas in the lamp 2, to render the lamp conducting. The main discharge condenser 26 thereupon discharges its energy violently into the lamp 2, to produce an arc discharge between the cathode 4 and the anode 6 through the lamp 2. Part of this energy is transformed into a pulse of useful light. A brilliant flash of light is, therefore, produced by the lamp 2 when the condenser 26, after being charged to a certain value, discharges its energy violently and quickly into it at the desired instant, in response to the stimulus produced upon the band electrode 100 by the impulse surge in the secondary winding 29 of the flashing transformer 30. The potential upon the grid 50 controls the time of starting of the violent electrical transients that are transformed into useful light. The condenser 26 thus discharges through the mercury-pool tube 2 once corresponding to each pulse of the transformer 51.

The arc through the lamp 2 is not maintained, because of the action of the tube 7 which prevents current flow to the tube 2. The condenser 26 is again charged at a predetermined time before the next discharge, and a flash of light is obtained from the tube 1.

The inductance of the conductors 8 and 10 is useful in extinguishing the arc, as it tends to make the discharge current oscillatory.

At the instant of discharge, the current surge through the lamp 2 is very great. It may be over one thousand amperes. The flash of light through the tube is very intense and quick. The apparent speed of a moving object is thus effectively reduced or "stopped," since the object moves an inappreciable distance during the time that the light is on. Because of the low impedance of the mercury lamp 2, the voltage across the resistor 33 is zero, or even negative, after the condenser 26 has become fully discharged, allowing the tube to deionize; and the duration of the flash discharge is short, the time taken for the circuit to function being about 10 microseconds or less, the exact time being a function of the size of the capacity 26, the voltage to which it is charged, the dimensions of the tube, the temperature of the tube, the impedance of the leads 8 and 10 connecting the condenser and the tube, the volt-ampere characteristics of the tube 2, and other factors. Under some conditions, the duration of the flash is less than one microsecond.

The pulses producing the flashes therefore occur during times very short compared to the intervals of time between the pulses and flashes.

As the thyratron 140 is a rectifier, the current in the circuit comprising the condenser 26 and the transformer 30 cannot oscillate, although there is a tendency to do so. At the instant that the current stops, due to the oscillation, the tube 140 begins to deionize, since the grid and plate voltages, at this instant, are both either negative or zero with respect to the cathode 48. The charging current of the condenser 26 causes a voltage drop across the resistance 31, which is negative with respect to the cathode 48. This voltage drop is nearly equal to the voltage of the direct-current supply, as the battery 101, at the first instant, but becomes smaller as the con-

denser 26 is charged. After the production of the light pulse, the condenser 26 becomes again charged, as from the battery 101 or other direct-current supply, through the impedance 31, in preparation for the next impulse.

Immediately after the condenser 26 discharges, the grid 50 is caused to be very negative with respect to the cathode 48 and, in this manner, the thyratron is prevented from starting as the condenser 26 builds up and the anode becomes positive with respect to the cathode.

The thyratron trip circuit puts a high voltage on the starting band 100 in a sudden manner that makes the tube start reliably. The use of this starting-tube thyratron makes the mercury-arc stroboscope a practical and useful arrangement. The mercury-arc tube may thus be started by a few microamperes of current in the grid circuit of the control tube, and there is a negligible time delay between the current impulses to the grid and the starting of the light flashes.

One characteristic of the present invention is that the light produced by the tube 2 may be of much higher instantaneous intensity than is attainable with mercury tubes the light of which is continuous, instead of periodic.

Under the control of its trip circuit, through the flash transformer 30a, in the same manner as before described, a potential will be impressed upon the control electrode 100 in the control or starting path of the tube 7, to render the first normally non-conductive stroboscopic or rectifier tube 7 suddenly conductive. The principal current path of the tube 7 therefore becomes effective to charge the capacitor 26 from the direct-current source 21. The same type of current impulse that has before been described as initiated, during the discharge of the condenser 26, through the principal-current path of the tube 2, will therefore be initiated in the principal current path between the principal electrodes 4 and 6 of the tube 7, during the charging of this same condenser 26. Where repetitive or periodic flashing is desired, the potential will be impressed upon the starting or control electrode 100 of the tube 7 intermittently or periodically to initiate current pulses in the principal-current path of the tube 7, between its principal electrodes 4 and 6, intermittently or periodically.

The first stroboscopic or rectifier tube 7, however, is energized in advance of the second tube 2. This energization occurs for a predetermined interval of time during the pulse of current that is transmitted to the above-described condenser-charging circuit to charge the condenser 26. A flash is obtained in the first tube 7 during this charging of the condenser 26. It is not until after the condenser 26 has thus become charged that a pulse of current becomes transmitted through the starting-current path of the tube 2. Current flow is initiated, under the action of the capacitor 26, through the principal-current path, between the cathode 4 and the anode 6, of the tube 2. This results in a second flash, this time through the second tube 2.

The two before-described thyratron trip circuits, therefore, intermittently feed alternately into the primary windings 36, 36a of the transformers 30 and 30a that start the tubes 7 and 2. The tubes 2 and 7 are thus energized alternately to charge and discharge the condenser 26 alternately.

The thyratrons are tripped alternately by connecting their grids 50, 50a to a source 141 of alternating voltage by transformers 51 and 51a

which are 180 degrees out of phase, or by any other means, to accomplish the desired result. The circuit is especially effective at high frequency since the time for deionization is long.

Modifications will occur to persons skilled in the art, and all such are considered to fall within the spirit and scope of the invention, as defined in the appended claims.

What is claimed is:

1. In combination, an electric-discharge device having a principal-current path defined by a plurality of principal electrodes and a starting-current path extending from a starting electrode for initiating current flow in said principal path, a capacitor connected between said principal electrodes, means for charging said capacitor including another discharge device having a plurality of principal electrodes and a control electrode, means for normally maintaining said last-named discharge device deenergized, means for intermittently applying a potential between said control electrode and one of the said last-named principal electrodes such that the said last-named discharge device is energized for a predetermined interval of time and during said interval of time transmits a pulse of current to charge said capacitor, and means for transmitting a pulse of current through said starting path after said capacitor has been charged to initiate current flow through said principal path under the action of the potential of said capacitor.

2. In combination, an electric-discharge device having a principal-current path defined by a plurality of principal electrodes and a starting-current path extending from a starting electrode for initiating current flow in said principal path, a capacitor connected between said principal electrodes, means for charging said capacitor including a normally deenergized discharge device having a plurality of principal electrodes and a control electrode, means for periodically applying a potential between said control electrode and one of the said last-named principal electrodes such that the normally deenergized discharge device is energized for a predetermined interval of time and during said interval of time transmits a pulse of current to charge said capacitor, means for periodically transmitting a pulse of current through said starting path after said capacitor has been charged to initiate current flow through said principal path under the action of the potential of said capacitor, and means for varying the periodicity of the transmission of the pulse of current.

3. In combination, an electric-discharge device having a principal-current path defined by a plurality of principal electrodes and a starting-current path extending from a starting electrode for initiating current flow in said principal path, a capacitor connected between said principal electrodes, means for charging said capacitor including a normally deenergized discharge device having a plurality of principal electrodes and a control electrode, means for intermittently applying a potential between said control electrode and one of the said last-named principal electrodes such that the normally deenergized discharge device is energized for a predetermined interval of time and during said interval of time transmits a pulse of current to charge said capacitor, a second capacitor, means for charging the second capacitor, and means for connecting said second capacitor, after it has been so charged, to said starting path, whereby a pulse of current is transmitted through said starting path and current

flow is initiated from the first-named capacitor in said principal path.

4. In combination, an electric-discharge device having a principal-current path defined by a plurality of principal electrodes and a starting-current path extending from a starting electrode for initiating current flow in said principal path, a capacitor connected between said principal electrodes, means for charging said capacitor including a normally deenergized discharge device having a plurality of principal electrodes and a control electrode, means for intermittently applying a potential between said control electrode and one of the said last-named principal electrodes such that the normally deenergized discharge device is energized for a predetermined interval of time and during said interval of time transmits a pulse of current to charge said capacitor, and means for transmitting a pulse of current through said starting path after said capacitor has been charged to initiate current flow through said principal path under the action of the potential of said capacitor.

5. In combination, an electric-discharge device having a principal-current path defined by a plurality of principal electrodes and a starting-current path extending from a starting electrode for initiating current flow in said principal path, a capacitor connected between said principal electrodes, means for charging said capacitor including a normally deenergized discharge device having a plurality of principal electrodes and a control electrode, means for periodically applying a potential between said control electrode and one of the said last-named principal electrodes such that the normally deenergized discharge device is energized for a predetermined interval of time and during said interval of time transmits a pulse of current to charge said capacitor, and means for periodically transmitting a pulse of current of current through said starting path after said capacitor has been charged to initiate current flow through said principal path under the action of the potential of said capacitor.

6. An electric system having, in combination, normally non-conductive gaseous-conductor means having a normally ineffective principal-current path defined by a plurality of principal electrodes and a control path extending from a control electrode for initiating pulses of current in the principal path, a capacitor, a source of potential, means connecting the capacitor and the gaseous-conductor means in the principal path to the source to charge the capacitor from the source when the principal path is effective, means for intermittently impressing a potential upon the control electrode in the control path to render the gaseous-conductor means suddenly conductive intermittently in order to render the principal path intermittently effective to charge the capacitor intermittently from the source, thereby intermittently to initiate pulses of current in the principal path between the principal electrodes, and means whereby the pulses are caused to occur during times short compared to the intervals between the pulses.

7. An electric system having, in combination, normally non-conductive gaseous-conductor means having a normally ineffective principal-current path defined by a plurality of principal electrodes at least one of which is composed of mercury and a starting-current path extending from a starting electrode for initiating pulses of current in the principal path, a capacitor, a source of potential, means connecting the capaci-

tor and the gaseous-conductor means in the principal path to the source to charge the capacitor from the source when the principal path is effective, means for intermittently impressing a potential between the control electrode and one of the principal electrodes to render the gaseous-conductor means suddenly conductive intermittently in order to render the principal path intermittently effective to charge the capacitor intermittently from the source, thereby intermittently to initiate pulses of current in the principal path between the principal electrodes, and means whereby the pulses are caused to occur during times short compared to the intervals between the pulses.

8. An electric system having, in combination, normally non-conductive gaseous-conductor means having a normally ineffective principal-current path defined by a plurality of principal electrodes, a capacitor, a source of potential, means connecting the capacitor and the gaseous-conductor means in the principal path to the source to charge the capacitor from the source when the principal path is effective, means for intermittently rendering the gaseous-conductor device suddenly conductive in order to render the principal path intermittently effective to charge the capacitor intermittently from the source, thereby intermittently to initiate pulses of current in the principal path between the principal electrodes, and means whereby the pulses are caused to occur during times short compared to the intervals between the pulses.

9. A light-flash producer having, in combination, normally non-conductive gaseous-conductor means for producing light flashes of substantial illumination intensity having a normally ineffective principal-current path defined by a plurality of principal electrodes, a capacitor, a source of potential, means connecting the capacitor and the gaseous-conductor means in the principal path to the source to charge the capacitor from the source when the principal path is effective, and means for rendering the gaseous-conductor means suddenly conductive in order to render the principal path effective to charge the capacitor from the source, thereby to initiate a pulse of current in the principal path between the principal electrodes to produce suddenly a light flash of substantial illumination intensity.

10. A light-flash producer having, in combination, normally non-conductive gaseous-conductor means for producing light flashes of substantial illumination intensity having a normally ineffective principal-current path defined by a plurality of principal electrodes and a control path extending from a control electrode for initiating a pulse of current in the principal path, a capacitor, a source of potential, means connecting the capacitor and the gaseous-conductor means in the principal path to the source to charge the capacitor from the source when the principal path is effective, and means for impressing a potential upon the control electrode in the control path to render the gaseous-conductor means suddenly 65

conductive in order to render the principal path effective to charge the capacitor from the source, thereby to initiate a pulse of current in the principal path between the principal electrodes to produce suddenly a light flash of substantial illumination intensity.

11. A light-flash producer having, in combination, normally non-conductive gaseous-conductor means for producing light flashes of substantial illumination intensity having a normally ineffective principal-current path defined by a plurality of principal electrodes, a capacitor, a source of potential, means connecting the capacitor and the gaseous-conductor means in the principal path to the source to charge the capacitor from the source when the principal path is effective, means for intermittently rendering the gaseous-conductor means suddenly conductive in order to render the principal path intermittently effective to charge the capacitor intermittently from the source, thereby intermittently to initiate pulses of current in the principal path between the principal electrodes to produce suddenly light flashes of substantial illumination intensity, and means whereby the flashes are caused to occur during times short compared to the intervals between the flashes.

12. A light-flash producer having, in combination, normally non-conductive gaseous-conductor means for producing light flashes of substantial illumination intensity having a normally ineffective principal-current path defined by a plurality of principal electrodes and a control path extending from a control electrode for initiating pulses of current in the principal path, a capacitor, a source of potential, means connecting the capacitor and the gaseous-conductor means in the principal path to the source to charge the capacitor from the source when the principal path is effective, means for intermittently impressing a potential upon the control electrode in the control path to render the gaseous-conductor means suddenly conductive intermittently in order to render the principal path intermittently effective to charge the capacitor intermittently from the source, thereby intermittently to initiate pulses of current in the principal path between the principal electrodes to produce suddenly light flashes of substantial illumination intensity, and means whereby the flashes are caused to occur during times short compared to the intervals between the flashes.

HAROLD E. EDGERTON.
